APPARATUS FOR SPRAYING FLUID INTO
TUBULAR MEMBERSMeredith C. Brown, Whittier, Calif., assignor to
Pacific Clay Products, Los Angeles, Calif., a cor-
poration of California

Application April 26, 1948, Serial No. 23,273

7 Claims. (Cl. 118—306)

1

This invention is concerned with spraying apparatus and it is a general object of the invention to provide apparatus for effectively, uniformly, and economically spraying fluid onto inaccessible parts or surfaces such, for example, as the interior of pipes, or the like.

The apparatus of the present invention may be used under various circumstances or in various situations. However, it is particularly applicable to and practical for spraying a glaze, or the like, onto the interior of clay products such, for example, as pipes or like articles. Such products have heretofore been sprayed by apparatus requiring a blast or jet of air to cause atomizing of the glaze.

A general object of the invention is to provide apparatus operable to spray glaze or the like uniformly and in the desired manner and faster than is possible with the ordinary air type spray or atomizer.

As an example of a practical application of the present invention reference will be made to the spraying of the interior of sewer pipe, or the like, prior to its being fired. In the manufacture of sewer pipe and like products the clay or body out of which the pipe is manufactured is suitably formed into an elongate tubular structure and before it is fired the glaze is applied, usually by spraying it onto the interior of the pipe. The material used for glazing sewer pipe, or the like, is usually a fusible or vitreous material finely divided or ground and suspended in water. The glazing material is highly abrasive and the spraying or atomizing equipment ordinarily used for handling fluid involving water laden with glazing material will not satisfactorily withstand the abrasive action of the glazing material and, consequently, often wears or cuts out in a matter of but a few hours use.

A general object of the present invention is to provide spraying apparatus which is simple and convenient to handle and to clean, and which serves to uniformly and advantageously spray fluid laden with abrasive material such as glazing material. The apparatus of the present invention is such that it can be handled in much the same manner that ordinary spraying equipment is handled, but instead of depending upon an atomizing action gained through a nozzle with finely adjusted or delicate parts subject to rapid wear or deterioration, or through the use of air delivered under pressure through a hose, or the like, the desired action is gained by impinging a solid stream of fluid against a baffle plate from which the material spreads in the

desired manner to be deposited upon the object to be coated. With my invention no air flow or stream is required and, therefore, the apparatus is wholly without an air duct or hose such as is usually required in spraying apparatus.

Another object of the present invention is to provide spraying apparatus of the general character referred to involving a spray head supplied with fluid through an elongate tubular body, which head involves a control valve, a simple nozzle delivering a solid high-velocity jet of fluid, and a baffle plate forward of the nozzle and in the path of the jet or stream of fluid and of such character as to effectively disperse the fluid in all directions in order to uniformly deposit the fluid onto the interior of a pipe, or the like. The construction of the present invention is such that it will not easily clog or become inoperative and it is such that when repair or replacement does become necessary the parts can be reached or renewed very easily and quickly.

Another general object of the present invention is to provide a spray head of the general character referred to including a baffle plate of such form or design that the material or fluid directed onto the plate is dispersed radially therefrom and air is entrained by the dispersed fluid as it leaves the plate, to the end that the fluid is effectively broken up or atomized.

Another general object of the present invention is to provide a spray head of the general character referred to involving but few simple parts and in which the parts subject to handling fluids under high velocities are very hard, in fact, are harder than the abrasive material contained in the fluid, to the end that the head will operate satisfactorily over a long period of time. In accordance with the structure of the present invention the parts required to be manufactured of very hard material, such as tungsten carbide or the like, are of very simple form and are few in number.

Another object of the present invention is to provide a spraying apparatus of the general character referred to involving a simple, practical, easily operated arrangement of parts, all of which make the apparatus inexpensive of manufacture and practical to use.

The various objects and features of my invention will be fully understood from the following detailed description of typical preferred forms and applications of the invention, throughout which description reference is made to the accompanying drawings, in which:

Fig. 1 is a side elevation of the apparatus provided by the present invention, showing it in use in connection with a typical length or section of sewer pipe, part of the pipe being broken away to illustrate the spray head located therein. Fig. 2 is a perspective view of the spray head provided by the present invention with parts broken away to illustrate the interior construction. Fig. 3 is an enlarged longitudinal detailed sectional view taken as indicated by line 3-3 on Fig. 1. Fig. 4 is an enlarged transverse sectional view taken as indicated by line 4-4 on Fig. 1. Fig. 5 is an enlarged detail transverse sectional view taken in the direction indicated by line 5-5 on Fig. 1. Fig. 6 is an enlarged detailed sectional view taken as indicated by line 6-6 on Fig. 4. Fig. 7 is an enlarged side elevation of the baffle plate of the spray head showing the manner in which it is supported. Fig. 8 is an enlarged detailed sectional view taken as indicated by line 8-8 on Fig. 1. Fig. 9 is an enlarged detailed sectional view taken as indicated by line 9-9 on Fig. 1, and Fig. 10 is a view similar to Fig. 5, showing a second form of construction.

The spraying apparatus of the present invention may be used to spray various fluids onto various articles. However, it is particularly practical for the spraying of a fluid bearing finely divided vitreous material or glaze and for applying such fluid to the interior of sewer pipe, or the like. In the drawings the work or object worked upon is illustrated as a length of pipe P and it is shown supported in a horizontal position by a suitable support A, the support being shown as involving a trough-like horizontally disposed rest 10 carried by suitable standards 11.

The apparatus involving or embodying the present invention is a manually operable unit and involves, generally, an elongate tubular body B, a handle C at the outer end of the body, a spray head D at the inner end of the body, a fluid supply line E delivering fluid to the body, preferably to the outer end portion thereof, control means F for the head D, guide means G supporting the head relative to the work or pipe P, and stop means H limiting the extent to which the head may be inserted in the pipe P. The present invention further involves the provision of certain parts of such hardness as to resist the abrasive action of the fluid being handled, and as a result of providing certain parts of the hardness hereinafter described the structure is rendered practical and economical to use.

The body B is preferably a straight elongate tubular element such as a length of pipe or tubing, and it has its rear end joined to the handle C while its forward end carries the head D. In the particular case illustrated the rear end portion of the body is externally threaded at 12 for connection with the handle, while the forward end portion of the body is internally threaded at 13 to receive the head D. In the form of the invention illustrated the handle C involves a sleeve-like part or fitting 14 into which the rear end of the body is threaded, while the head D has an externally threaded rear end portion that is engaged in the threaded part 13 at the forward end of body 10.

The handle C located at the rear end of body B is shown as involving, generally, a grip 15, a neck portion 16 from which the grip depends and the fitting 14 which is carried by the neck portion so that it is horizontally disposed and

somewhat forward of the upper end portion of the grip. The grip 15 is preferably a pistol type grip so that it is comfortable and convenient to hold. In the case illustrated the handle is a continuous or integral unit having the grip, neck and fitting integrally joined as a single casting, or the like.

The spray head D provided by the present invention involves, generally, a valve 20, a nozzle 21, baffle means 22 and a bracket 23 supporting the baffle means. The valve 20 is joined to or carried by the forward end of the body B while the nozzle 21 is joined to and carried by the forward end of the valve 20. The bracket 23 is carried by or mounted on the structure formed by the valve and nozzle, and it supports the baffle means 22 in the path of the stream of fluid delivered by the nozzle.

In the form of the invention illustrated the valve 20 involves, generally, a tubular case X, a seat Y carried in the case, and a valve member Z cooperating with the seat.

The case X of the valve is an elongate tubular part with an inlet end portion 25 joined to body 25 B and with an outlet end portion 26 extending forward and carrying the nozzle 21. The outlet portion 26 is considerably smaller in diameter than the inlet portion 25 through which construction an internal rearwardly facing shoulder 27 is established in the case, as clearly shown in Fig. 2 of the drawings. The rear end portion of the valve case is threaded and engaged in the forward end of body B, while the forward end portion of the case is externally threaded and receives the bracket 23 and also the nozzle 21.

The seat Y is a simple tubular part snugly engaged in the inlet portion 25 of the case to rest or bear upon the seat 27. The seat has a straight round or turned exterior 30 having a press fit in the opening of the case portion 25. The ends of the seat are flat and the inner end rests upon or engages the shoulder 27. The seat has a central bore or opening extending through it, the rear end portion 30 of the opening through the seat being enlarged somewhat and tapered to properly cooperate with the valve Z.

The valve Z is a simple elongate centrally disposed part with its forward end portion or tip tapered to have cooperative engagement with the tapered opening 31 of the seat. When the valve Z is forward it seats in the opening 31 closing the passage through the seat. As the valve is withdrawn or moved rearwardly flow is permitted through the seat and through this construction the rate of flow can be accurately governed.

The nozzle 21 in the form of the invention illustrated involves a cap 33 and a tip or orifice member 34 carried by the cap. The cap 33 is joined to the forward end of the valve case being threaded onto the forward threaded portion 35 of the case portion 26. The cap is a simple part with a center bore or opening 37 formed through it.

The tip or orifice member 34 is a simple bushing-like part tight in the cap 33, being tightly seated in the bore 37 of the cap. The tip has an enlarged part or flange 40 at its forward end seating against the forward end of the cap and the outer forward corner 41 of the flange is beveled away, as clearly shown in Fig. 2 of the drawings. The tip has a flow passage 44 entering it from its rear end and it has a reduced or jet 70 opening 45 communicating with the opening 44

and extending to and open at the forward end of the tip.

Through the construction just described fluid passed by the valve 20 enters the tip of the nozzle and issues in a fine solid stream from the jet opening 45. It is to be observed that with the construction just described flow through the head is substantially parallel with the longitudinal axis of the head, there being a minimum of deflection of the stream or flow and there being a total absence of tortuous passages, ducts, or openings through which the fluid must pass and which are characteristic of ordinary atomizing heads.

The baffle means 22 involves a baffle plate having a flat front face 50 and a beveled or receding peripheral edge 51. The plate is preferably round or disc-shaped and the face 50 of the plate is flat and smooth. The bracket 23 supports the baffle plate in line with the nozzle or so that the stream issuing from the nozzle impinges upon the center of the plate and the plate is supported so that the plane of its face 50 is normal to the axis of the nozzle or of the stream issuing from the nozzle.

The peripheral edge or portion 51 of the plate is an important feature of the present invention. The edge portion is beveled or pitched so that it recedes forward from the face 50. The face 50 and the receding edge 51 define a sharp peripheral edge 52 on the plate from which the material impinging upon the plate issues radially. The radial flow from the edge 52 causes air to be drawn in along the receding peripheral edge 51, with the result that the air is picked up or entrained in the radial flow and serves to effectively atomize the liquid so that it is dispersed in the desired manner.

The bracket 23 is shown as including a collar 55 carried on the portion 26 of the valve case and an outwardly bowed arm 56, which is carried by the collar and extends laterally and forward and then transversely of the axis of the head to support the baffle plate forward of the nozzle, and in the manner hereinabove described.

In practice the baffle plate may be mounted on the outer end of arm 56 in any desired manner. In the case illustrated the arm 56 is shown provided with an enlargement or head 58 with a threaded opening receiving a threaded shank 59 projecting from the baffle plate. The baffle plate is fixed or permanently secured to the forward end of the shank as by welding, brazing or other suitable means. By rotating the shank in the head 58 the space between the nozzle and baffle plate may be adjusted. A lock nut 60 is carried on the shank 59 to be tightened against the head 58 for fitting the plate in the desired adjusted position.

In the form of the invention shown in Figs. 1 to 9 the arm 56 is round in cross section, being formed of a bar or length of tool steel, or the like. In practice, as the spray issues radially from the baffle plate it must pass the arm 56 before reaching the surface to be sprayed. In practice I may employ an arm 56 which is streamlined in cross section, as shown in Fig. 10, so that the arm has a minimum effect upon the radial flow from the baffle plate to the surface being sprayed.

The supply line E is preferably joined to the rear end portion of body B and in practice it may be a length of flexible hose 61, or the like, and it may be joined to the body by means of a T-fitting 62 inserted in the rear end portion of

the body immediately ahead of the fitting 14, as clearly shown in Fig. 3 of the drawings.

The control means F is shown as involving, generally, a trigger 70 operating a stem 71 which is joined to the valve Z in the head D. In the preferred arrangement the trigger is pivotally carried by the handle C and the stem 71 extends longitudinally through the body B. The trigger is shown pivoted to the neck portion 16 of the handle and depends therefrom immediately forward of the grip 15 to be in position to be conveniently operated by a finger of a hand grasping the grip. In the particular construction illustrated the trigger has a yoked upper end portion having side plates 72 which straddle or embrace the lower edge portion of the neck 16 to which they are connected by a suitable pivot pin 73.

The stem 71 is preferably an integral rearward extension or continuation of the valve Z, being a rod-like part that extends rearwardly through body B to issue therefrom through the fitting 14. In the case illustrated the stem is shown passing through suitable packing 75 carried by the fitting 14. An enlarged part or shank portion 76 is provided on the rear end of the stem, that is, rearward of the fitting 14, and the shank portion 76 extends between the plate portions 72 of the trigger. Trunnions 77 project inwardly from the plate portions and extend into a recess 78 in the shank portion 76 providing an operative connection between the trigger and the stem.

The connection just described is such that as the trigger is pivoted or swung the stem is reciprocated. The shank portion 76 of the stem continues rearwardly from the trigger and is slidably entered in a guide opening 80 in the upper end portion of the grip 15, the opening 80 being in line with the body B. The rear end portion of the guide opening 80 is closed by a plug 81 and a compression spring, preferably a helical spring 82, is carried in the opening 80 between the plug 81 and the rear end of shank portion 76 of the stem. Through this construction the spring normally yieldingly urges the stem forward or to a position where the valve Z is closed.

The guide means G is joined to or carried by the rear end portion of the structure, preferably by the handle C, and involves, generally, an elongate arm 83 projecting forward from the rear of the structure, and a contact member 84 supported by the arm laterally removed from the head D and engageable with a guide part such as the exterior 85 of the pipe P. In the case illustrated the arm 83 is connected with or carried by the neck 16 of the handle C and projects forwardly therefrom to be parallel with and laterally offset from the body B. The arm 83 is preferably tubular so that it is rigid and at the same time as light as possible.

The contact element 84 is preferably a roller and is shown supported from the arm 83 through a hanger having a collar 86 carried on the arm and depending side plates 87 between which the roller is arranged. A roller shaft 88 extends between the side plates 87 and rotatably supports the roller. In the particular case illustrated the plates 87 have vertically disposed slots or guideways 89 in them passing the end portions of the shaft, and clamp nuts 90 are carried on the end portions of the shaft to be tightened against the outer sides of the plates. Through this construction the roller can be readily adjusted vertically in the hanger as circumstances may require.

The collar 86 is slideable lengthwise of the arm 83 so that the roller can be adjusted to any desired position above the body B. In the case illustrated the collar 86 is a split collar adapted to be clamped onto the arm by a clamp screw 91. 5
In the preferred arrangement of parts the hanger is located lengthwise of the arm 83 so that the roller 84 is supported in the vicinity of the head D and is laterally offset from the head, so that the head is supported concentrically in 10 the pipe P.

The stop means H is intended to limit the extent to which the head can be inserted in the pipe P. In the case illustrated the stop means involves a split sleeve 93 slidably carried on the arm 83 to be set against movement along the arm by means of a clamp screw 94. A stop plate 95 depends from the sleeve 93 and has an opening 96 passing the body. It will be apparent that the stop plate can be set in any desired position lengthwise of the body and in practice it is set so that it engages the end of pipe P through which the head is inserted to stop the head in the desired position at the other end portion of the pipe.

The fluid ordinarily applied to the interior of a pipe P is made up of water carrying glaze which is finely divided vitreous or fusible material and is ordinarily highly abrasive. Through the present invention the head D that handles the fluid carrying the abrasive material is such as to have but three parts subject to wear or to being cut out by the fluid, these being the seat Y, the tip 34 and the baffle plate supported by the bracket 23. In accordance with the present invention these particular parts are made of a material harder than the abrasive material carried in the fluid, it being preferred in practice to form them of tungsten carbide, or the like. It is significant to note that these particular parts are all of very simple form or design, making it possible to manufacture them economically of exceedingly hard material, such as tungsten carbide. Further, in carrying out the invention it is desirable that the various other parts of the head, and particularly the bracket arm 56, be formed of hard material such as hard or hardened steel so that the abrasive material handled does not cause excessive wear. In practice it has been found desirable to form the bracket arm 56 of hardened tool steel.

From the foregoing description it will be apparent how the apparatus of the present invention can be operated or handled with reference to a pipe P and it is to be observed that the flow of fluid is controlled at the head or by means of the valve in the head from the control means, the trigger of which is remote from the valve of the head. The operator grasping the grip of the handle can readily depress or operate the trigger causing the valve of the head to open, whereupon the material under pressure supplied to the hose 61 flows through the body and is discharged from the head issuing in a solid stream from the tip of the nozzle, which stream impinges upon the baffle plate so that the fluid is spread radially in all directions and with the result that air is drawn into the radially dispersed liquid, causing atomization or dispersion, to the end that the material is uniformly and most effectively distributed onto the interior surface of the pipe. By moving the head through the pipe either into the pipe or from the pipe, as the material is sprayed by the head, the en-

tire interior of the pipe may be coated in the desired manner.

Having described only a typical preferred form and application of my invention, I do not wish to be limited or restricted to the specific details herein set forth, but wish to reserve to myself any variations or modifications that may appear to those skilled in the art and fall within the scope of the following claims:

Having described my invention, I claim:

1. Apparatus for spraying fluid into a tubular member including, an elongate tubular body to be inserted in said member, a spray head on the forward end of the body including a valve, a nozzle and a baffle plate forward of the nozzle, a fluid supply line connected with the rear end portion of the body, a handle at the rear end of the body carrying the body, a control including a trigger carried by the handle and a stem operated by the trigger and actuating the valve, a guide carried by the handle including an arm extending forward from the handle above and parallel with the body to overlie said member and a contact roller carried by the forward end portion of the arm to contact the exterior of said member, and stop means limiting insertion of the body into said member.

- 30 2. Apparatus for spraying fluid into a tubular member including, an elongate tubular body to be inserted in said member, a nozzle at the forward end of the body to direct a stream of fluid forward from the body, fluid supply means delivering fluid for the nozzle, a manually operated valve for controlling flow of fluid through the
35 nozzle, a handle at the rear end of the body and a guide carried by the handle including an arm extending forward from the handle above and parallel with the body to overlie said member and a contact roller carried by the forward end
40 portion of the arm to contact the exterior of said member.

3. A sprayer of the character described for co-operation with work having faces at opposite sides thereof including, an elongate body, a handle on one end of the body, a spray means on the other end of the body, and guide means attached to the handle at a point spaced from the body and projecting from the handle in spaced relation to the body and substantially parallel therewith and having a work engaging part engageable with one face of the work while supporting the body with the spray means directing fluid to the other face of the work.

4. A sprayer for applying fluid to the interior of an open ended tubular object including, an elongate body insertable in the object from one end to have an inner end within the object and an outer end at the exterior of the object, an elongate guide element laterally removed from the body and substantially parallel and coextensive therewith, a member extending between and spacing one end of the guide element and outer end portion of the body, said member rigidly connecting the body and guide element at the exterior of the object, a part on the other end of the guide element engageable with and movable along the exterior of the object, and fluid spraying means on the inner end portion of the body for directing fluid into the interior of the object.

5. A sprayer for applying fluid to the interior of an open ended tubular object including, an elongate tubular body insertable in the object from one end to have an inner end within the object and an outer end at the exterior of the ob-

ject, an elongate guide element laterally removed from the body and substantially parallel and coextensive therewith, means coupling one end of the guide element and outer end portion of the body together at the exterior of the object, a roller on the other end of the guide element engageable with and movable along the exterior of the object, a spray nozzle on the inner end of the body for spraying fluid onto the interior of the object, means supplying fluid to the outer end portion of the body, a valve for controlling flow of fluid to the nozzle, a handle at the outer end of the body, and operating means for the valve including a manually operated element adjacent the handle.

6. A sprayer for applying fluid to the interior of an open ended tubular object including, an elongate tubular body insertable in the object from one end to have an inner end within the object and an outer end at the exterior of the object, an elongate guide element laterally removed from the body and substantially parallel and coextensive therewith, means coupling one end of the guide element and outer end portion of the body together at the exterior of the object, a roller on the other end of the guide element engageable with and movable along the exterior of the object, a spray nozzle on the inner end of the body for directing a stream of fluid from the inner end of the body, a baffle plate spaced from the nozzle in the path of such stream directing fluid onto the interior of the object, means supplying fluid to the outer end portion of the body, a valve for controlling flow of fluid to the nozzle, a handle at the outer end of the body, and operating means for the valve including a manually operated element adjacent the handle.

7. A sprayer for applying material to the interior of an open ended tubular object including, an elongate body with a forward end portion insertable into the object from one end thereof, an

elongated guide adapted to extend parallel with the body and spaced laterally therefrom, the guides being engageable with the exterior of the object, a handle at the rear end of the body to occur at the exterior of the object, the handle supporting the guide at a point spaced from the body, means supplying fluid to the body, a head on the forward end of the body including, a valve for receiving fluid from the body, a nozzle to receive fluid through the valve and to deliver a stream of fluid forward from the body, a baffle plate, and a bracket supporting the plate in the path of such stream to direct fluid laterally of the stream, and means controlling the valve of the head, the valve including a tubular case connected to the forward end of the body, a seat in the case and a needle member cooperating with the seat, and the nozzle including a cap on the forward end of the case and an orifice member carried by the cap, and the bracket including a sleeve carried by the case and an outwardly bowed arm carried by the sleeve and projecting forward therefrom.
